BUNCH AND FILLING BUILDER

Bud M. Newsom and Sam Burge,
Montgomery, Ala.

Application September 11, 1935, Serial No. 40,147

1. Claim. (Cl. 242—43.7)

The invention relates to a bunch and filling builder and more especially to a filling and bunch builder mechanism for yarn winding machines and spinning frames that are adapted to lay a preliminary winding or bunch on the bobbins or yarn receivers prior to the laying of the main service winding thereon.

The primary object of the invention is the provision of mechanism of this character, wherein the same is wholly automatic in its operation and is adjustably carried by the frame of the machine so that the latter will run twenty-five to thirty minutes longer according to the number of yarn and effects the winding of the thread 10 tighter on the bobbin, eliminating all high end pieces and places a great deal more yarn on the bottom of the bobbin and materially minimizes waste.

Another object of the invention is the provision of mechanism of this character, wherein the yarn production is greatly increased both in spinning and weaving and results in a better grade of cloth.

A further object of the invention is the provision of mechanism of this character, wherein the filling runs from two to two and one-half minutes longer in shuttle.

A still further object of the invention is the provision of mechanism of this character, which is simple in construction, thoroughly reliable and efficient in its operation, readily and easily applied to the frame of a spinning machine, wholly automatic in the working thereof and inexpensive to manufacture and install.

With these and other objects in view, the invention consists in the features of construction, combination and arrangement of parts as will be hereinafter more fully described, illustrated in the accompanying drawing, which discloses the preferred embodiment of the invention, and pointed out in the claim hereunto appended.

In the accompanying drawing:

Figure 1 is a fragmentary front elevation of a spinning machine showing the builder mechanism constructed in accordance with the invention applied thereto.

Figure 2 is an enlargement of a sufficient portion of the machine with the builder mechanism made clear in its construction and manner of operation.

Figure 3 is an end elevation of the builder mechanism.

Similar reference characters indicate corresponding parts throughout the several views in the drawing.

Referring to the drawing in detail, the invention herein illustrated is applied to a ring spinning machine wherein the head end A is fastened to bolster rails 10 the top of which supports a series of spindles provided with whirls 11 for rotating a series of yarn bobbins 12 mounted on the spindles. A lifter rail 13 has a series of rings 14 provided with the usual travelers and is supported by a lifter rod 15, the lower end 16 of which rests upon a roll 17 mounted on the cross 10 arm lever 18 pivoted at 19 upon a hanger 20 extending from the bottom of the bolster rail 10. The lever 18 is counterbalanced by a weight 18' whereby the upward traverse of the ring rail is effected. Extending upward from the lever 18 15 is a segment arm 21 to which is connected a chain, in this instance including two separate lengths 22 and 23, respectively, and the section 23 passes over the sheave pulley 24 and is then connected to the filling winding lever 25 working in conjunction with the builder lever 26 of usual construction pivoted on a stud 27 fixed to the head end A. While only a single lever 18 and lifter rod 15 are shown it is to be understood that any suitable number of these may be used and may be connected, as usual, to move in unison to cause the ring rail 13 to move up and down under the control of the builder motion as is common and well understood in ring spinning machines. The winding lever 25 to which the 30 builder motion chain, that is the section 23 thereof, is attached derives its motion from the rack 28 through action of a roll (not shown) fastened to the rack and coacting with the upper surface of the winding lever 25. Motion is imparted to the rack by the worm connection of a shaft 29. An intermittent motion is imparted to the shaft 29 by the ratchet 30 fixed thereon acting in conjunction with the pawl 31 carried on the arm 32 which is actuated by the rod 33 as the 35 builder lever 26 is raised and lowered. These parts and their assembly are disclosed in Letters Patent No. 1,491,808 dated April 29, 1934.

To suit particular requirements as to speed in the laying of the yarn onto the bobbin there 45 is arranged an inverted substantially T-shaped bracket 34 upon the frame of the spinning machine and this bracket at the base arm 35 has provided therein an elongated slot 36 for accommodating fasteners 37 mounted in the rail 10 50 thus it being seen that the said bracket 34 is susceptible of adjustment longitudinally of this rail 10 to alter or change the position of the bracket.

In the vertical stem portion of the bracket 34 55

is a perpendicular slot 38 for vertical adjustable mounting therein of the attaching end 39 of a stud journal 40 which is horizontally disposed. Loosely journaled on the stud 40 is a cam 41 having several stepped cam portions 42 and 43, respectively, and to the latter is hinged at 44 the chain length 22 while to the portion 42 is hinged at 45 the chain length 23 and under movement of these lengths in unison 10 with each other a slow motion of the rail at the lower part of the spindles is secured and then gradually the motion is quickened at the upper part of said spindles whereby a larger number of yards of yarn may be wound on each spindle.

15 As indicated in Figures 1 and 2 of the drawing the cam 41 in its connection with the lengths 22 and 23 of the chain is such that when the chain is moved the said cam will be rotated for a part of a revolution. When the up and down 20 travel of the rail 13 is begun said travel is usually at one and three-eighths inches but could be any desired number of inches and this travel is continually and gradually increased until the bobbin is full and the travel of the rail has increased to one and three-fourths inches. This 25 increase of travel takes place after the bottom of the bobbin is filled with yarn to the desired diameter and the length of travel is caused by the initial setting of the bracket 34 which setting is fixed by the fasteners 37. The original 30 travel of the frame is one and three quarters inches and when setting the travel for one and three-eighths inches stroke such remains until the cam 41 revolves to a point where its flat 35 surface 42 disengages chain length 23 which then rides onto the circular portion of said cam. This causes the stroke of the rail to increase to the natural stroke of one and three-fourths inches.

The provision of the cam 41 causes the speed 40 of the rail 13 to increase as the cam 41 turns over due to the chain length 23 riding on to the surface 43 of the cam 41 at a greater distance from the center of rotation than the surface 42 (see Figure 3). It is to be noted that 45 when the mechanism first starts the cam 41 is in the position as shown in Figures 1 and 2 and the chain length 23 is at the smallest diameter of the cam 41 and as the latter rotates this chain length 23 rides onto the larger diameter of said cam. The first part of the rotation of the cam 41 will cause the rail 13 to move gradually upwardly at substantially an even speed and when the chain length 23 engages the larger diameter of the cam 41 the speed will gradually increase 50 in the movement of the rail 13 and in this manner of action the bobbins will be threaded tighter, eliminating all high end pieces and a great deal more yarn is placed on the bottoms of the bobbins and also a larger amount of yarn is wound 55 60 and this amount being arranged near the bases of the spindles.

In order to effect the winding of the yarn in

the form of a bunch at the lower part of the bobbin the traverse of the ring rail is retarded by means of a locking latch 46 abutting against the builder lever 26. The latch is pivoted on a stud 47 fixed in a bracket 48 in stationary relation to the framing of the machine; the latch being provided with an abutment member 49 adjustably mounted on the lower part of the latch and a knock-off roll (not shown) operating in conjunction with said lever to release the lock- 10 15 20 25 30 35 40 45 50 55 60 65 70 75 80 85 90 95 100 latch 46.

In operation the operative after starting the machine depresses the ring rail by means of foot pressure applied to the end of the lever 18 thus positioning the ring rail for the beginning of the bottom traverse of the yarn. This action also depresses the builder lever to its lowest position acted thereon by the cam (not shown) of the builder structure as disclosed in Patent No. 1,491,808. The operative then manually swings the latch 46 so that the part 49 rests on top of the lever 26 preventing it from moving upwardly thus rendering the ring rail stationary and causing the yarn to wind in a bunch; meanwhile, the rotating motion of the cam gradually brings the lug cam into contact with the knock-off roll, the shape of the lug cam being such that the locking action of the latch is removed from the builder lever and in consequence the builder lever resumes its upward and downward motion without restriction thus permitting the main winding of the yarn on the bobbin in the regular manner. The latch after being pushed from contact with the builder lever swings to such a position as to be just out of the path of the motion of the builder lever.

What is claimed is:

The combination with a flexible element for connection to a ring rail, a bunch builder, and a flexible builder element for actuation by the bunch builder, of rotatable means interposed between and attached to said elements for transmitting motion therebetween at variable speeds, said means including a rotating member to which the respective elements are connected, the member being formed with a peripheral recession to provide cam surfaces at different distances from the axis of said member and having the flexible elements attached to said surfaces respectively, and a bracket adjustably attached to a frame of a spinning machine and having a horizontally disposed elongated slot therein, means passing through the frame and slot for securing the bracket in selected horizontally adjusted position on the frame, said bracket also having an elongated slot disposed at substantially right angles to the first slot, a stud journal supporting said rotating member and adapted to be mounted adjustably in the second slot, and means for securing said journal in selected position in said second slot.
